(57) **CLAIM**

(30) **Foreign Application Priority Data**

The ornamental design for a document camera, as shown and described.

Nov. 5, 2018 (JP) 2018-024287

DESCRIPTION

(51) **LOC (12) Cl.** **16-01**

FIG. 1 is a top, front and left side perspective view of a document camera showing our new design;

(52) **U.S. Cl.**

FIG. 2 is a front view thereof;

USPC **D16/211**; D16/232; D14/423

FIG. 3 is a back view thereof;

(58) **Field of Classification Search**

FIG. 4 is a right side view thereof;

USPC D16/200, 202-204, 208, 211, 218, 219,

FIG. 5 is a left side view thereof;

D16/221, 225, 229, 232; D14/423, 429,

FIG. 6 is a top plan view thereof;

D14/251; 348/373-376; 396/430, 431,

FIG. 7 is a bottom plan view thereof;

396/535, 539-541

FIG. 8 is a top, front and left side perspective view showing the document camera in an alternate position;

CPC G03B 17/02; G03B 19/04; G03B 17/56;

FIG. 9 is a top, front and left side perspective view showing the document camera in a second alternate position;

G03B 17/04; G03B 15/03; G03B 17/48;

FIG. 10 is a top, front and left side perspective view showing the document camera in a third alternate position; and,

G03B 17/06; H04N 5/2251; H04N

FIG. 11 is a top, front and left side perspective view showing the document camera in a fourth alternate position.

5/2252; H04N 5/2253; H04N 5/2254

The broken lines depict portions of the document camera in which the design is embodied that form no part of the claimed design.
